(57) **CLAIM**

I claim the ornamental design for a propeller-shaped cup outer lid, as shown and described.

DESCRIPTION

FIG. 1 is a perspective view of a propeller-shaped cup outer lid showing my new design;

FIG. 2 is a top view thereof;

FIG. 3 is a bottom view thereof; and,

FIG. 4 is a side view thereof.

The ornamental design which is claimed is shown in solid lines in the drawings. The shaded areas and broken lines in the drawings are for illustrative purposes only and form no part of the claimed design.
